Atty.

UNITED STATES PATENT OFFICE.

JOHN WILLIAM EGAN, OF TORONTO, ONTARIO, CANADA.

CUT-OUT PLUG.

1,356,611.

Specification of Letters Patent. Patented Oct. 26, 1920.

Application filed October 15, 1919. Serial No. 330,859.

To all whom it may concern:

Be it known that I, JOHN WILLIAM EGAN, a subject of the King of Great Britain, and resident of 107½ Danforth avenue, in the city of Toronto, county of York, Province of Ontario, in the Dominion of Canada, have invented certain new and useful Improvements in Cut-Out Plugs, of which the following is a specification.

10 The invention relates to improvements in cut-out plugs, as described in the present specification and shown in the accompanying drawings that form a part of same.

15 The invention consists essentially of the novel features of construction whereby the electric circuit may be broken within the plug.

20 The objects of the invention are to provide a means for breaking the electric circuit other than by disengaging one or other of the terminal plugs, to provide a device especially adapted for use in connection with electric irons, toasters and other like devices, to reduce to a minimum the strain on 25 the electric wiring, and generally to provide a cut-out plug which will be inexpensive to construct, simple and safe to operate durable and efficient.

30 In the drawings Figure 1 is a plan view of a plug with one side thereof removed.

Fig. 2 is a longitudinal sectional view through the casing taken on the line A—A of Fig. 1, the sliding conductor being shown in full.

35 Fig. 3 is a plan view of the device assembled.

Like numerals of reference indicate corresponding parts in the various figures.

Referring to the drawings 1 and 2 are 40 the two halves of the casing composed of fiber, rubber or other non-conductive material such as is usual in the construction of devices of this nature, said halves or sections being adapted to be secured together by bolts 3 and nuts 4 as customary.

45 5 are contact terminals adapted to receive the pins or other form of projections from the device to which the current is to be supplied, said contact terminals being contained 50 in parallel longitudinal slots 6 extending inwardly from the ends of the sections 1 and 2.

55 7 are substantially U shaped spring clips secured to the inner ends respectively of the contact terminals 5 and projecting inwardly therefrom in the slots 6, the ends of said

clips preferably being turned outwardly to form guides for the jumpers.

8 are terminal lugs located at the opposite end of the casing from the terminals 5 and 60 to which the wires 9 are adapted to be secured.

10 are spring clips secured to the lugs 8 respectively and projecting inwardly therefrom a short distance in slots 11, said 65 clips 10 being considerably shorter than the clips 7.

12 are jumpers composed of metal strips 70 slidable longitudinally of the casing in slots in the sections 1 and 2, said jumpers being 75 of such a length that when drawn to the extreme inner ends of the clips 7 the other ends thereof will terminate considerably short of the ends of the clips 10 thus breaking the connection between said clips 7 and 75 10 but when drawn into the clips 10 the other ends will still engage the clips 7 and thus form a means of completing the electric circuit between the opposing terminals.

13 is an elongated block composed of non 80 conductive material and sliding in a longitudinal slot 14 located between the jumpers 12, said block being connected to said jumpers and being for the purpose of providing a means for moving the two jumpers in 85 unison.

The jumpers are shown in the drawings as being provided with opposing offsets 15 secured to opposite sides of the block 13 and sliding in suitable grooves in the casing 90 but it is apparent that said jumpers and said block may be secured together in various ways such as by providing the block with right angle extensions which may be secured to said jumpers.

95 The block 13 is provided with a lug 16 preferably located at the extreme end adjacent to the clips 10 and adapted to project through a slot 17 in one of the sections of the casing to provide a means for operating 100 the jumpers.

18 is the usual guard composed of coiled wire having a reinforced end 19 adapted to be inserted in a slot in the casing.

105 In the operation of this invention the plug is connected to the iron or other device in the usual way, that is to say the projections from said device are inserted in the clips or contact terminals 5, and the lug 16 is then drawn to the extreme head end of 110 the slot 17 in the casing which has the effect of drawing the jumpers into engage-

ment with the clips 10 and completing the circuit between the terminals 5 and 8.

When the device is sufficiently hot or when for any other reason it is desired to shut off the current for an indefinite time it is simply necessary to push the lug 16 to the opposite end of the slot 17 which frees the jumpers from engagement with the clips 10 and breaks the circuit.

10 This device will be found of decided advantage in cases where it is not convenient to turn off the current at the usual switch, such as when the device is being used in connection with a toaster which is usually located on the dining table whereas the usual switch is frequently a considerable distance away.

What I claim is:

20 In a cut out plug, a casing, divided centrally and forming sections adapted to be detachably secured together, contact terminals parallelly arranged in slots extending inwardly from one end of said casing,

spring clips secured to the inner ends of said terminals and projecting inwardly, terminal 25 lugs located in slots from the other end of said casing, spring clips secured to the inner ends of said lugs and projecting inwardly and terminating short of the first mentioned clips and being shorter than said 30 first mentioned clips, jumpers in continuous engagement with the clips from said contact terminals and slidable in said casing to engage the clips from said terminal lugs, a non-conductive block slidable in said casing between said jumpers and secured to offsets from said jumpers and a lug from said block extending through one section of said 35 casing and operating in a slot therein.

Signed at the city of Toronto this 4th 40 day of October 1919.

JOHN WILLIAM EGAN.
